ATTORNEY

UNITED STATES PATENT OFFICE.

CLARENCE A. BECKETT, OF WILKINSBURG, PENNSYLVANIA.

WRITING IMPLEMENT.

1,235,096.

Specification of Letters Patent. Patented July 31, 1917.

Application filed March 28, 1917. Serial No. 158,042.

To all whom it may concern:

Be it known that I, CLARENCE A. BECKETT, a citizen of the United States, residing at Wilkinsburg, in the county of Allegheny 5 and State of Pennsylvania, have invented certain new and useful Improvements in Writing Implements, of which the following is a specification.

This invention relates to fountain pens 10 and particularly to the cap for covering the pen point which thoroughly protects said point from injury and dirt, and through which the pen may be thrust when it is desired to use the pen for writing purposes, 15 thus avoiding the necessity and trouble of withdrawing the cap from over the pen point and placing the same on the opposite end of the pen and then reversing this operation after writing to cover and protect the 20 point.

With the above objects in view, the invention consists in the novel construction, combination, and arrangement of parts herein-after described, pointed out in the appended 25 claims, and illustrated in the accompanying drawing, in which—

Figure 1 is an elevation of a portion of a fountain pen provided with the improved cap.

Fig. 2 is a similar view of the fountain pen, the cap, however, being shown in central longitudinal section.

Fig. 3 is an end view of the cap, and

Fig. 4 is a sectional view of the outer end 35 of the improved cap with the pen thrust therethrough in position for use.

In the drawings 10 indicates a fountain pen, or pen of other type, pencil or like implement, and 11 a cap fitting snugly over 40 the pointed end of the pen for protecting the point 12. The cap 11, as shown, is provided near its lower open end on diametrically opposite sides with bow springs 13 that are convexed outwardly and seated in 45 suitably shaped grooves 14, formed in the cap on the inner side thereof. These springs press against the sides of the pen 10 and serve to hold the cap securely but removably on the end of the same. The outer end of 50 the cap 11 is flanged inwardly as at 15 for a short distance leaving a central nearly circular opening 16 in the end of the cap, through which the pen point 12 and a short length of pen 10 may be thrust. The opening 55 16 is under-cut, as at 17, and adapted to fit said opening and its under-cut portion

is a shutter 18 pivoted at 19 to the flange 15 and forming a tight closure when in position for the end of the cap. At one side of the cap a short distance below its outer end 60 is a button 20 from the inner side of which there projects a short stem 21 that passes through a longitudinal slot 22 in the cap and serves to guide the button when moved by the finger. The slot 22 is preferably 65 made L-shaped, as shown in dotted lines in Fig. 1, to permit the button to be turned laterally when moved downwardly its full distance for the purpose of locking the same in its depressed position. On the inner end 70 of the stem 21 is an eye in which is fastened one end of a relatively stiff coil spring 23, the opposite end of said spring being attached to the shutter 18 diametrically opposite the hinge 19, and being an expansion 75 spring serves to hold the door closed when the button is in the normal position shown in Figs. 1 and 2.

In use, the pen point 12 will be protected by the cap 11 placed over the end of the 80 pen handle and held thereon by the spring 13. The button 20 being at its outermost position will, through the medium of the spring 23, force the shutter 18 into its seat and thereby close and seal the end of the 85 cap to prevent the entrance of dust and protect the pen point. When, however, it is desired to use the pen for writing purposes instead of slipping the cap from the pen handle, the button 20 is drawn downwardly, 90 pulling the spring 23 and the latter in turn swings the shutter 18 open, as clearly shown in Fig. 4. The button may now be turned into the angular portion 24 of the slot 22 locking the shutter open. Then, by slipping the cap 11 down upon the pen handle 10, the point will be thrust through the opening 16 in position for use. After writing the cap will be moved in the opposite direction, the stem 21 disengaged from the 95 angular portion of the slot 22 and the button pushed to the outer end thereof, thereby closing the shutter and returning the parts to normal position.

What I claim is:

1. A cap for protecting the point of a writing implement having an opening in its outer end, a swinging closure for said opening, sliding means on the outside of said cap extending inwardly through a hook 110 shaped slot therein for closing and opening the closure and locking the same in open

- 2
- position, and a spring connection between said closure and the sliding means.
2. A cap for protecting the point of a writing implement having an opening in its outer end, a closure therefor hinged to said end and adapted to swing inwardly, a sliding button on the side of the cap, and a connection between the button and the closure.
- 10 3. A cap for protecting the point of a writing implement comprising a tubular member adapted to slip over the point of said implement and having an opening in its outer end, a closure for said opening hinged to said end and adapted to swing inwardly, a button slidable longitudinally on one side of said cap, and a resilient connection between the button and the closure.
- 15 4. A cap for protecting the ends of a writing implement comprising a tubular member adapted to slip over the pointed end of said implement and having an opening through its outer end, an inwardly swinging shutter pivoted to said end for closing said opening, a button slidable longitudinally on the side of said cap, a stem projecting inwardly from said button through a longitudinal slot in the cap, and a spring connection between said pin and the shutter.
- 20 In testimony whereof I affix my signature 25 in presence of two witnesses.
- CLARENCE A. BECKETT.
